UNITED STATES PATENT OFFICE.

CHARLES HALBREICH, OF NEW YORK, N. Y.

MACHINE FOR MAKING PAPER DISHES.

No. 926,866.

Specification of Letters Patent.

Patented July 6, 1909.

Application filed January 3, 1908. Serial No. 409,155.

To all whom it may concern:

Be it known that I, CHARLES HALBREICH, a subject of the Czar of Russia, and resident of New York city, borough of Manhattan, in the county of New York and State of New York, have invented certain new and useful Improvements in Machines for Making Paper Dishes, of which the following is a specification.

10 The object of my invention is to provide a machine to fold suitably cut and scored paper blanks into dish-like form and for simultaneously interlocking the fastening portions of the blanks, and to this end my invention 15 comprises the novel details of improvement and combination of parts that will be more fully hereinafter set forth and then pointed out in the claims.

Reference is to be had to the accompanying drawings forming part hereof, wherein—

Figure 1 is a plan view of a machine embodying my invention, part being broken away, Fig. 2 is a longitudinal section thereof. Fig. 3 is a cross section illustrating, on opposite sides of the line *a*, different positions of the operating parts, Fig. 4 is a plan view of a blank for the paper dish. Fig. 5 is a side view of a folded dish, partly in section at the left of the line *b*, and Fig. 6 is an end view of 30 the folded dish, partly in section at the left of the line *c*.

Similar numerals and letters of reference indicate corresponding parts in the several views.

35 The numeral 1 indicates a suitable frame, whose bed or table-like portion 1^a is suitably disposed forming a cavity 2 into which the dish folding members or die parts fit. At 3 is a vertically movable plate having side 40 members 4, hinged to its edges, end members 5 hinged to its ends, and corner members 6 hinged at the corners or angles between the adjacent members 4, 5, the members 4, 5, 6 being adapted to rest upon the flat portion of 45 the table when plate 3 is raised, as in Fig. 2, and at the left in Fig. 3. The bottom of cavity 2 is shown provided with suitable recesses 2^a into which the hinges 7 may pass when the parts are depressed. The side 50 walls of cavity 2 are inclined downwardly and inwardly, as at 2^b, beneath the corresponding members 4, 5, 6, to cause said members to fold upwardly when plate 3 is depressed. Plate 3 is normally pressed and 55 held upwardly by one or more suitable springs, and in order to guide said plate in its

up and down movements I have shown the same provided with depending plungers 8 that are guided in suitable bearings 9 in table 1^a, said plungers having flanges 8^a to limit their upward movement, springs 10 shown within said plungers and bearing against caps 11 secured on table 1^a, serving normally to raise plate 3, the arrangement being such that when plate 3 is raised to its uppermost position and limited by flanges 8^a bearing against the table part the folding members 4, 5, 6 will extend outwardly substantially in line with plate 3. Above the parts 3, 4, 5, 6, and reciprocative with respect thereto is a 70 pressing plate 12, carried by rod or post 13, and to the edges of plate 12 are hinged folding members 14 that lie over the members 4, and to the ends of plate 12 are hinged folding members 15 that lie over the members 5. 75

To the members 14 and 15 are pivotally connected upwardly extending links 16, the upper ends of which are shown forked at 16^a and carry pins 17 (preferably provided with anti-friction rolls) that enter vertical slots 18 80 in guides or wings 19 secured to post 13, which guides or wings are shown projecting from a sleeve 20 secured on said post. When post 13 is raised above plate 3, as in Fig. 2 and at the left in Fig. 3, the members 14 and 85 15 will be suspended in an outward position by links 16 and guides 19, but when said post is depressed to fold a blank for a dish the parts 17 will slide upwardly through the slots 18 for causing pressure from wings 19 90 through links 16 to the members 14 and 15 for pressing the dish blank, as at the right in Fig. 3.

The blank to be folded in dish form is shown in Fig. 4, and has a centrally disposed 95 portion A, side portions B, end portions C, and corner portions D, all weakened by the score lines E, shown in dotted lines, to permit proper folding of the blank. The end portions C of the blank have slots C' and the 100 edges of said portions C are cut on lines converging outwardly, at C², while the corner portions D are cut on lines D' at an angle to the edges C², to provide tongues F, and notches G are cut in the outer or extreme 105 edges of the corner portions D to engage the material at the outer ends of the slots C' when the tongues F are pushed through said slots, in the manner shown in Fig. 6, to lock the corner portions D to the corresponding 110 end portions C. The blank is of such dimensions as to fit properly between the folding

members previously described. In order to open the slots C' of the blank so that the tongues F may slide through said slots I provide the members 5 with depressions or sockets 5^a on their upper surfaces and the members 15 having corresponding projections 15^a suitably aligned with the sockets 5^a, so that when a blank is in position between the folding members, as in Fig. 2, and the upper members 10 pressed upon the lower members the projections 15^a will press the parts of the blank that lie between the corresponding slots C' into the sockets 5^a to open the slots C' and thus permit the tongues F to slide into said 15 slots.

To cause proper operation of the parts above described I have shown post 13 connected with a cross bar or beam 20, and post 13 is shown movably connected to said cross bar by being adapted to slide in a bearing 20^a in said bar, said post having a head 13^a and a collar 21 suitably secured to the post, a spring 22 fitting between the cross bar and collar 21, all whereby post 13 will be moved 25 up and down with the cross bar but the latter will act resiliently to prevent undue pressure and injury to the parts, but the tension of the spring will be sufficient to cause proper folding of the dish blank by the folding members. Said cross bar or beam 20 is rigidly connected with depending arms 23 which travel in upright guides 24 secured upon frame 1, and links 25 are pivotally connected with said arms and with cranks 26 at 30 the ends of a shaft 27 suitably journaled in frame 1, whereby cross bar or beam 20 is reciprocated. At 28 is a shaft journaled in frame 1 and shown provided with a drive pulley 29 and also provided at opposite ends 35 with gears 30 that mesh with gears 31 on shaft 27 for rotating the latter.

I have also shown means for cutting the blanks for the dish from a continuous strip of paper or other suitable material A², cutting 45 the outlines of the various portions of the blank, and scoring the same, and for also feeding the cut and scored blanks to the folding devices intermittently. For this purpose I provide a roll 32 that is journaled in 50 suitable bearings upon frame 1, and is provided upon its periphery with projecting cutters, arranged so that in one revolution of the roll the blank will be cut to the required width from strip A² by the cutter 33, while 55 the cutter parts 34 cut the outer edges of the corner portions D of the blank, the cutter parts 35 cut the notches G, the cutter parts 36 cut the outer portions of the tongues F, the cutter parts 37 cut out the angular piece 60 between the edges C² and D', and other cutters score the lines E in the blank, while suitable cutters form the slots C' and cut other necessary portions of the blank, the cutters being similar at opposite ends of the roll, and 65 also similar on opposite sides of the longitudi-

dinal blank separating cutter 33 so that as roll 32 revolves once a complete blank will be cut, scored, and severed from strip A². A corresponding roll 32^a is journaled in frame 1 beneath roll 32 and has suitable cavities in 70 its surface that correspond with the cutters of roll 32 to permit the operation of the cutters thereon; said rolls also serve to feed the paper strip and blank. The rolls 32 and 32^a are connected by gears 38, 39 to rotate in 75 unison. At 40 is a roll journaled in suitable bearings on frame 1, between roll 32 and the folding members, and rotated in unison with roll 32 by a gear 41 meshing with gear 38. Roll 40 has suitable projections 40^a, similarly arranged and disposed near opposite ends thereof, adapted to engage the cut out pieces of the dish blank and push such pieces through suitable openings 1^b in frame 1 (see Fig. 2), so that such pieces will not be 85 carried along with the blank to the folding members. The rolls 32, 32^a and 40 may be intermittently rotated to accord with the operations of the folding members in any suitable manner. For this purpose I have 90 shown shaft 28 provided with a broken gear 42 having a suitable number of teeth for part of its circumference and the remainder of the circumference provided with no teeth, said teeth being adapted to engage a pinion 95 43 secured upon a shaft 44, suitably journaled in frame 1, and carrying a gear 45 that meshes with a gear 46 secured on shaft 32^b of roll 32^a. By this means, as shaft 28 rotates it may cause continuous reciprocation of 100 post 13 and the blank folding members, while rolls 32, 32^a and 40 will be intermittently rotated and so timed as to push the paper blanks between the upper and lower set of folding members at such time as the 105 upper set of folding members are raised.

The operation of the machine may be described as follows. As the upper set of folding members rise a folded dish H may be removed by hand or by any suitable means, 110 and then a cut blank will be pushed over the lower set of folding members by means of the next following blank, in position shown in Fig. 2, and when the upper set of folding members descend they will bear upon the 115 blank and thereby push the blank and the lower set of folding members into cavity 2 carrying the central plates 3 and 12 straight down and holding the central part A of the blank firmly, while at the same time the 120 hinged folding members will fold upwardly in the manner shown at the right in Fig. 3, thereby bending the blank on the score lines E, and the projections 15^a will push the parts 125 of the blank that lie between the slots C' into the recesses 5^a and, as the corner folding members 6 fold upwardly, the corner portions D of the blank will be caused to slide inwardly behind the end portions C thereby carrying the tongues F into the slots C', and 130

by one compressing action of the folding members the side, end, and corner portions of the blank will be folded in dish form, as shown in Figs. 5 and 6, with the tongues F 5 projected through the corresponding slots C' and locked by the notches G. When the upper set of folding members next rise the folded dish H may be removed while another blank is next presented between the sets of 10 folding members, so that at each complete down and up stroke of post 13 a dish may be folded and its tongues locked in the corresponding slots, the lower set of folding members rising under the influence of springs 10 15 at each elevation of post 13.

Having now described my invention what I claim is:

1. The combination of a table having a cavity provided with inwardly and downwardly inclined walls, a plate adapted to enter said cavity and provided with members hinged at its edges to engage the inclined walls of the cavity, a reciprocative plate aligned with the first named plate and provided with members hinged at its edges, means to cause the second named members to press upon the first named members when folded, and means to reciprocate said plates and members.
2. The combination of a table provided with a cavity, a plate aligned with said cavity and provided with members hinged at its edges, means to resiliently support said plate, a post, a plate secured to said post and provided with members hinged at its edges, guides carried by said post, links movably connected with said guide and pivotally connected with the second named hinged members, and means to reciprocate said post.
3. The combination of a table provided with a cavity, a plate aligned with said cavity, means to movably support said plate, folding members hinged at the edges of said plate, a post, a centrally disposed plate carried by said post and provided with members hinged at its edges, a cross bar movably connected with said post, a spring interposed between said cross bar and said post, and means to reciprocate said cross bar.
4. The combination of a table provided with a cavity, a movable plate aligned with said cavity and provided with members hinged near its edges, plungers connected with said plate, guides for said plungers, means to limit the upward movement of the plungers, springs to raise said plate, a post having a plate disposed over the first named

plate and provided with members hinged at its edges, means to cause said hinged members to press upon a blank, and means to reciprocate said second named plate and members.

5. The combination of a table provided with a cavity, a centrally disposed plate over the cavity, and provided with members hinged at its edges, means to resiliently support said plate; a post provided with a plate disposed over the first named plate and having members hinged at its edges and disposed over the corresponding first named hinged members, said post having guides above its plate, links pivotally connected with the hinged members of the post and movably connected with said guides, and means to reciprocate said post.

6. The combination of a table having a cavity, a movable plate over the cavity and having folding members hinged at its edges, a reciprocative centrally disposed plate over the first named plate; folding members hinged thereto at its edges, means to cause said plates and members to coact in pressing a blank interposed between them, a pair of rolls one of which is provided with cutters arranged to cut and score a blank and cut the blank from a continuous strip, and the other roll having depressions corresponding to said cutters, a roll located between the first named rolls and the folding members and provided with projections aligned with openings in the table to push pieces out from the blank through said openings, and means to intermittently rotate said rolls during reciprocations of said folding members.

7. The combination of a table having a cavity, a movable plate over the cavity and having folding members hinged at its edges, a reciprocative centrally disposed plate over the first named plate, folding members hinged thereto at its edges, means to cause said plates and members to co-act in pressing a blank interposed between them, the folding members at opposite ends of one of said plates being provided with recesses, and the opposed members connected with the other plate having projections aligned with the recesses.

Signed at New York city, in the county of New York and State of New York this 2nd day of January, A. D. 1908.

CHARLES HALBREICH.
